UNITED STATES PATENT OFFICE.

GLENN BENNER AND BURR S. ROGERS, OF LINDSEY, OHIO.

MAIL-BAG CATCHER.

No. 853,572.

Specification of Letters Patent.

Patented May 14, 1907.

Application filed August 1, 1906. Serial No. 328,779.

To all whom it may concern:

Be it known that we, GLENN BENNER and BURR S. ROGERS, citizens of the United States, residing at Lindsey, in the county of Sandusky and State of Ohio, have invented new and useful Improvements in Mail-Bag Catchers, of which the following is a specification.

This invention relates to mail bag catchers; and the principal object of the invention is to provide a device of this class with a locking device, adapted to securely hold the mail bag or pouch when the latter is engaged by the catcher, preventing rebound of such bag or pouch, and the consequent danger of its being thrown to the ground and ground to pieces under the wheels of the train.

A further object of the invention is to improve and to simplify the construction and operation of the locking device, and to render the latter absolutely certain and efficient in operation.

A still further object of the invention is to provide a simple and improved means for unlatching or releasing the locking device in order to enable the bag or pouch to be conveniently detached from the catcher.

Further objects of the invention are to simplify and improve the general construction and operation of the parts of the device.

With these and other ends in view, which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise details therein exhibited, but that changes, alterations and modifications within the scope of the invention may be resorted to, when desired.

In the drawings,—Figure 1 is a top plan view of a mail bag catcher constructed in accordance with the principles of the invention. Fig. 2 is a sectional detail view of a portion of the same. Fig. 3 is a perspective detail view of the trip-lever used for releasing the spring catch of the locking device.

Corresponding parts in the several figures are indicated by like characters of reference. The improved mail bag catcher comprises a body member A which consists of a casting

including two sleeves 1 and 2 disposed at an acute angle to each other. The sleeve 1 engages a rock shaft 3, upon which it is mounted for oscillation in the usual manner, said rock-shaft extending transversely across the door opening 4 of the mail car, a portion of the frame of which is shown at 5. In the sleeve 2 is mounted the inner end of the catcher-arm 6, which is provided with a hook 65 or recess 7 for the reception of the narrow portion of the mail bag or pouch. The sleeve 1 is provided with a handle 8, whereby it may be rocked so as to swing the pouch or bag through the door opening and into the car, in the usual manner.

The hook portion 7 of the catcher-arm is provided with a horizontal slot or recess 9 wherein is fulcrumed a locking lever 10; said lever has at its front end an arm 11 adapted to extend across the mouth of the hook 7 and into a recess 12 formed in the wall of the sleeve portion 2 of the casting A; the arm 11 has a terminal hook 13 adapted to be engaged by an opposing hook 14 formed upon a resilient member of spring 15 which is suitably secured within the recess 12. The hook members 13 and 14 are oppositely beveled so that they will automatically engage one another when the hooked end of the arm 11 85 moves within the recess 12.

At the rear end of the lever 10 there is formed an arm 16 which is adapted to ride within that portion of the slot 9 which extends through the curved portion or inner 90 end of the hook 7; that is to say, the arm 16, as will be seen by reference to Fig. 2, occupies this position when the arm 11 extends across the mouth of the hook 7. When the arm 11 having the hook 13 is disengaged 95 from the hook 14, the lever 10 will swing upon its fulcrum, under the impulse of a suitably arranged spring 17 bearing against the arm 16, until the latter swings to the position shown in Fig. 1 of the drawings, within the 100 recess portion of the hook 7, while the arm 11 swings out through the slot 9, to an unobstructing position with relation to the mouth of the hook 7, as clearly indicated in Fig. 1.

B designates a trip-lever, having a pivot 105 portion 18, whereby it is fulcrumed in the wall of the casting A in such a manner as to extend within the recess 12 of said casting where it is provided with an arm 19 adapted to bear against the hooked spring member 110 15; the opposite or outer end of the member 18 has an arm 20 which is connected by a link

21 with one arm 22 of a bell-crank which is pivoted upon the handle 8; the other arm of said bell-crank constituting a thumb-piece 23 whereby it may be conveniently manipulated.

- 5 The operation of this device will be readily understood from the foregoing description taken in connection with the drawings hereto annexed. The lever 10 is normally held by 10 the spring 17 in the position shown in full lines in Fig. 1 of the drawings, with the arm 11 in a non-obstructing position, and the arm 16 disposed partly or entirely within the recess of the hook 7. When a mail bag or 15 pouch is caught by the device, it will press against the arm 16, thus instantly swinging the lever 10 upon its pivot, causing the hooked arm 11 to swing into the recess 12 where it engages the spring catch 14, thus holding 20 the pouch or bag securely and positively preventing it from rebounding. The handle 8 is now manipulated to swing the bag into the mail car where it is released by a slight pressure upon the thumb piece 23, whereby the 25 trip-lever is operated to cause the arm 19 to displace the spring 15 until the hook or catch 14 at the free end of said spring is disengaged from the hooked end 13 of the arm 11 of lever 10; the latter being instantly restored to 30 normal position through the agency of the spring 17.

From the foregoing description taken in connection with the drawings hereunto annexed, the operation and advantages of this 35 invention will be readily understood. The device is simple in construction, and thoroughly efficient for the purposes for which it is provided.

What is claimed is:—

- 40 1. A mail bag catcher comprising a rock shaft, a sleeve mounted upon the rock shaft and provided with a handle, a sleeve extending at an angle to the first mentioned sleeve, a hook mounted in the last mentioned sleeve 45 and said hook provided with a slot, a lever pivoted in said slot and having terminal

arms, one of which may be moved into an obstructing position across the mouth of the receiving hook, a spring latch seated in a recess in the sleeve and a terminal hook upon 5c the obstruction arm for engaging said latch, substantially as described.

2. In a mail bag catcher, a body casting, a catcher-arm having a receiving hook connected with said casting and provided with a slot, a lever pivoted in said slot and having at one end an obstructing arm adapted to lie across the mouth of the hook and at the other end a bag-engaging arm that is confined within the slot when the former arm occupies an obstructing position, springs actuating the lever to swing the bag-engaging arm within the recess of the hook and the obstructing arm to a non-obstructing position, a spring catch within a recess in the body casting, a terminal hook upon the obstructing arm adapted to engage the spring catch, and means for moving the latter to a non-engaging position.

3. In a mail bag catcher, a body casting 70 having a handle, a catcher-arm having a receiving hook connected with the body casting and provided with a slot, a spring-actuated lever pivoted in said slot and having an obstructing arm and a bag-engaging arm, a 75 spring catch secured in a recess in the body casting and adapted for engagement with a terminal hook upon the obstructing arm, a trip lever pivoted in the body casting and having a spring catch engaging member at 80 its inner end, and an arm at its outer end, a bell-crank pivoted upon the handle of the body member, and a link connecting one arm of said bell-crank with the arm at the outer end of the trip lever.

85 In testimony whereof, we affix our signatures in presence of two witnesses.

GLENN BENNER.
BURR S. ROGERS.
